G. DE KOFF,
CUFF BUTTON.
FILED NOV. 17, 1921.

Witness:

F. C. Garrison

Inventor:
George De Koff
By Samuel N. Tond.
Atty.

UNITED STATES PATENT OFFICE.

GEORGE DE KOFF, OF CHICAGO, ILLINOIS.

CUFF BUTTON.

Application filed November 17, 1921. Serial No. 515,758.

To all whom it may concern:

Be it known that I, GEORGE DE KOFF, a citizen of Russia (who has made application for naturalization as a citizen of the 5 United States), residing at Chicago, in the county of Cook and State of Illinois, have invented certain new and useful Improvements in Cuff Buttons, of which the following is a specification.

10 This invention relates to cuff buttons of the link type, and the main object of the invention is to provide a simple and practical cuff button, which may be cheaply made, shall be easy to apply to and remove 15 from the cuff, and is efficient in use.

In the accompanying drawing I have 20 illustrated two practical forms of cuff buttons embodying the invention and both employing the same structural principle, and referring thereto—

Fig. 1 is a side elevation showing the button in the form which it appears when applied to the cuff;

Fig. 2 is a similar view, showing the 25 heads swung parallel to the link in position for insertion through, or removal from the button holes;

Fig. 3 is a top plan view of the button as shown in Fig. 1;

30 Fig. 4 is a cross-section on the line 4—4 of Fig. 2;

Fig. 5 is a view similar to Fig. 1 inverted, showing a modification;

Fig. 6 is a view similar to Fig. 3 of the 35 button shown in Fig. 5; and

Fig. 7 is an enlarged cross-section on the line 7—7 of Fig. 5.

Referring first to the embodiment of the invention shown in Figs. 1 to 4 inclusive, 40 10 designates the heads which may be of the general oval form shown, or of any other desired form, and are preferably of the concavo-convex surface form illustrated in Fig. 4. At diametrically opposite points on 45 the periphery of the head are integral lateral wings which are bent into rectangular form and folded inwardly on the rear side of the head, the free end portion of each being apertured as shown at 11 in Fig. 4, thereby 50 forming a pair of inwardly offset spaced hinge lugs 12, each having a limb extending inwardly substantially parallel with the

plane of the head and another apertured limb extending therefrom substantially at a right angle to the plane of the head. 55

13 designates as a whole the link, which is a one-piece member stamped out of a thin sheet metal blank. The ends of the link 13 are forked or branched as shown at 14, and on the free end of each branch 14 is a hinge 60 pintle 15 that is engaged with the hinge lug 12.

The structure illustrated in Figs. 5, 6 and 7 is closely similar to that hereinabove described, the only difference being that the 65 hinge lugs 12' are disposed further inwardly of the rear side of the head 10', and the branches 14' of the link 13' straddle the lugs with their hinge pintles 15' extending inwardly through the latter. 70

The heads are readily assembled with the link bar by simply bending the hinge lugs into engagement with the pintles of the latter. The heads with their hinge lugs and the link bar may be made by a simple punch 75 press, thus making the cost of manufacture very low.

In both forms of the invention, the flat link bar is preferably bowed or arched in its own plane, so as to give a slight relative 80 inclination to the heads 10 or 10', thus adapting the button for stiff cuffs, as well as soft cuffs.

I claim:

1. A cuff button, comprising a pair of 85 heads each formed with a pair of diametrically opposed rectangular apertured hinge lugs integral with and inwardly offset from the peripheries of said heads, and a connecting link bar having at each end thereof a 90 pair of hinge pintles pivotally engaged with said lugs.

2. A cuff button, comprising a pair of heads each formed with a pair of diametrically opposed hinge lugs integral with the 95 peripheries of said heads, each of said lugs having a limb extending inwardly substantially parallel with the plane of the head and another apertured limb extending therefrom substantially at a right angle to the plane of the head, and a connecting link bar having at each end thereof a pair of 100 oppositely extending hinge pintles pivotally engaged with the apertures of said lugs.

3. A cuff button, comprising a pair of heads each formed with a pair of diametrically opposed hinge lugs integral with the peripheries of said heads, each of said lugs having a limb extending inwardly substantially parallel with the plane of the head and another apertured limb extending there-

from substantially at a right angle to the plane of the head, and a connecting link bar having forked ends each terminating in a 10 pair of oppositely extending hinge pintles pivotally engaged with the apertures of said lugs.

GEORGE DE KOFF.
